(57) **CLAIM**

The ornamental design for an electronic calculator as shown and described.

DESCRIPTION

FIG. 1 is a reduced-scale front, left side perspective view of an electronic calculator showing our new design;

FIG. 2 is a front elevational view thereof;

FIG. 3 is a rear elevational view thereof;

FIG. 4 is a left side view thereof;

FIG. 5 is a right side view thereof;

FIG. 6 is an enlarged-scale top plan view thereof; and,

FIG. 7 is an enlarged-scale bottom plan view thereof.

The broken lines are included for the purpose of illustrating the environmental structure and form no part of the claimed design. The long and short dashed lines illustrate a boundary of claimed design and unclaimed ones.
